Application filed March 16, 1883. Term of patent 3½ years.

To all whom it may concern:

Be it known that I, ARTHUR L. HALLIDAY, of New York city, county and State of New York, have invented a new and original Design for Carpets, of which the following is a specification.

This invention relates to a new and original design for carpets and similar fabrics; and it consists in the novel grouping and configuration of parts, hereinafter more fully described.

The accompanying photograph illustrates a face view of a carpet having my new design.

C is a border containing an ornamentation of broken X-shaped figures interspersed with slender stalks. s is a band below the border C. H is a stripe containing an ornamentation composed of squares m, bearing a flowering spray, squares n, bearing an ornamentation of flowering branch, squares o, having also flower-like ornamentation, and squares r, bearing

an ornamentation of circular figures. These squares are set somewhat apart, and between them runs the figure t, consisting of rectilinear space bearing slender upright stalks with projecting leaves. Just above the figure n is the figure I, rectangular in shape, and bearing circular ornamentations.

I claim—

1. The design for carpets, consisting of the band C, substantially as shown.

2. The design for carpets, consisting of the band H, containing figures I, n, m, t, o, and r, substantially as shown.

3. The design for carpets, consisting of the band C, stripe s, and band H, containing figures I, n, m, t, o, and r, substantially as shown.
